UNITED STATES PATENT OFFICE.

JULIUS A. SCHWEIG, OF ST. LOUIS, MISSOURI.

LOCK FOR ELEVATOR DOORS.

Application filed May 21, 1928. Serial No. 279,255.

This invention relates to locks for elevator doors. One of the principal objects of the present invention is to provide a cheap and efficient lock which will prevent the opening 5 of the elevator doors when the car is not at a landing and which will prevent the operation of the elevator until all of the doors in the shaft are closed and locked. Another object is to prevent the lock and the switch 10 associated therewith from being closed when the door is opened. Other objects are simplicity of construction, ease of assembly and installation, and compactness and economy of design. The invention consists in the lock 15 and switch mechanism and the combinations and arrangements of parts hereinafter described and claimed.

In the accompanying drawings, which form part of this specification and wherein 20 like symbols refer to like parts wherever they occur;

Fig. 1 is an interior view of a portion of an elevator shaft at one of the door openings, showing a locking device embodying my invention mounted in the shaft in position to cooperate with the latch bar of a vertical sliding door;

Fig. 2 is an enlarged elevation of the shaft side of the lock and the parts associated 30 therewith, the cover plate being shown removed and the lock being shown in unlocked position;

Fig. 3 is a vertical section through the lock on the line 3—3 in Fig. 2;

Fig. 4 is a vertical section through the door opening showing the position of the parts when the car is at the landing and the vertical sliding door is opened;

Fig. 5 is a view similar to Fig. 4 showing 40 the position of the parts after the car has left the landing and the door is closed; and

Fig. 6 is a horizontal section through one side of the door opening on the line 6—6 in Fig. 1.

My invention is shown in connection with the shaft 1, car or cage 2, and the vertically sliding upper and lower door sections or gates 3 and 4, respectively, of an electrically operated freight elevator. As shown in the drawings, the upper and lower sliding sections 50 3 and 4, respectively, for each door opening in the elevator shaft are provided along each vertical edge with an angle bar side frame member 5 slidably arranged be-

tween angle bar guides 6 that are rigidly secured to each other and to the adjacent jamb members 7 of the door opening. The upper and lower door sections are counterbalanced preferably by means of chains 8 suitably connected to the lower corners of the upper door section. Said chains extend upwardly around pulleys (not shown) and are connected to the upper ends of upright chain rods 9, whose lower ends are secured to the upper corners of the lower door section 4 by means of door arms 10 that project horizontally therefrom.

The door is provided with a latch device comprising an operating lever 11, which is pivotally mounted for vertical swinging movement on the shaft side of the lower door section 4 near the middle of its upper end portion, and oppositely extending horizontally slidable latch bars 12, 12, whose inner ends are pivotally connected to the respective upper and lower arms of said operating lever. The free outer end portions of the latch bars 12 are slidably supported on rollers 13 mounted on the shaft side of the lower door section 4 and are adapted to be slid beyond the side edges of said section into engagement with suitable catches provided therefor at the sides of the door opening when the upper or handle end of the operating lever is swung upwardly. One end of a coil spring 14 is attached to one of the latch bars 12 and its other end is secured to a bracket 15 riveted to the shaft side of the lower door section, the parts being arranged so that the spring 14 tends to exert an outward pull on the latch bar and thus normally tends to hold the same in its projected position. The outer end of each horizontally slidable latch bar 12 is provided at its upper edge with a notch 16 forming a hooked end portion adapted in the latched or projected position of the latch bar, to cooperate with a locking device, which prevents unlocking of the door latching device when the elevator car is not at a landing and which also prevents the operation of the electric elevator until all the doors in the elevator shaft are closed and locked.

Said locking device comprises a box or casing 17, which is bolted or otherwise rigidly secured to one of the angle bar door guides 6 in position to cooperate with the notched outer end of the latch bar 12 in the projected position thereof. The

side of the casing which faces the outer end of the latch bar is provided with an opening 18 adapted to receive the outer hooked end of said bar; and the shaft side of said casing 5 is provided with an opening which is closed by means of a removable cover plate 19.

As shown in the drawing, the lower end of the front side wall of the lock casing 17 is provided with a beveled surface 17^a, adapted 10 to be engaged by the outer end of the latch bar 12 during the closing movement of the lower door section to cause said bar to slide inwardly against the pressure of the spring 14. The latch bar 12 is held in its retracted position by the lock casing 17 until said bar reaches a position opposite the opening 18 in the lock casing, in which position the hooked end of the bar is projected into said opening into engagement with the lock mechanism by the action of the spring 14.

Pivotaly mounted in the lock casing 17 for vertically swinging movement towards and away from the outer end of the latch bar 12 is an upright arm 20. The lower end 25 of the arm 20 is journaled on a horizontal pivot 21 fixed to the lock casing; and interposed between the inner edge of said arm and a lug 22 in said casing is a coil spring 23, which operates to swing the upper end of 30 said arm towards the outer end of the latch bar. Pivotaly mounted in a vertical slot provided therefor in the upper end of the arm is a catch 24, whose outer arm terminates in a downwardly projecting hook 25 adapted 35 to seat in the notch 16 in the outer end of the latch bar in the projected or latched position thereof. The inner arm of the catch 24 is adapted to abut against an inclined surface 26 formed at the top wall of the latch 40 bar receiving opening 18 in the lock casing when the latch bar 12 is retracted and the catch supporting arm 20 is swung forward by the action of the spring 23, thus causing the hooked end 25 of said catch to swing upwardly clear of the notch 16 in said bar 45 after said hooked end is moved clear of said opening. When the catch supporting arm 20 is swung rearwardly by the pressure of the latch bar thereagainst, the catch 24 is carried rearwardly through the opening 18 in the lock casing 17, and the hooked end 25 of said catch is permitted to swing downwardly into interlocking engagement with the notch 16 in the outer end of said latch 50 bar.

Mounted on a rock shaft 27 journaled in the lock casing 17 above the upper end of the latch supporting arm 20 and extending at right angles to the horizontal pivot therefor is a lever 28 having a downwardly extending lock arm 29 adapted to swing in front of the upper end of the catch supporting arm 20 in the rearward position thereof and thus prevent forward swinging movement thereof.

Rigidly secured to the shaft side of the upwardly extending arm 30 of the lock lever 28 is a fiber insulating block 31 which carries a pin 32 upon whose outer end is sleeved a metal contact plate 33. The contact plate 33, which forms one element of an electric switch, is preferably held on the pin 32 by means of a cotter pin 34; and a coil spring 35 is mounted on said pin between the insulating block 31 and the contact plate 33 for yieldably holding said plate in its outermost position. The other element of the electric switch comprises two contact members or posts 36 mounted on a fiber insulating block 37 which spans the lock casing 17 from side wall to side wall and is removably secured thereto by means of screws 38. The contact carrying lock lever 28 is swung into a position with its lock arm 29 in front of the upper arm of the catch supporting arm 20 to prevent forward swinging movement thereof. By means of a coil spring 39, which is sleeved on the rock shaft 27 for said lever with one end bearing against a lug 40 on the side wall of the lock casing and with the other end hooked over the shaft side of the lock arm of said contact carrying lock lever. As shown in the drawings, the stationary contact posts 36 are mounted on plates 41 that are provided with binding posts 42 which receive the wires of an electric circuit (not shown) for controlling the operation of the electric elevator.

The rock shaft 27 for the contact carrying lock lever 28 projects beyond the rear side wall of the lock casing and has a release arm 43 fixed thereto. Said arm preferably comprises a lower inner section fixed to the rock shaft 27 and an upper or outer section 44, which is adjustably secured to the outer end of the inner section and carries a cam roller 44^a at its outer end. The outer end of the release arm 43 projects inwardly into the elevator shaft 1 with its roller 44^a in position to be engaged by a retiring cam 45 mounted on the elevator car or cage. As shown in the drawing, the retiring cam comprises a vertically disposed cam plate that is secured to the elevator car 2 by parallel links 46, whereby said cam is adapted to be swung into and out of engagement with the cam roller 44^a on the release arm 43 of the lock when the car is at the landing. The retiring cam plate 45 is swung inwardly and upwardly to clear the cam roller 44^a preferably by means of a chain 47 whose lower end is secured to the upper link of the pair 46 and whose upper end cooperates with the motor (not shown) mounted on the elevator car. By this arrangement, the operation of stopping the car at the landing releases the chain 46 and thus permits the retiring cam 45 to swing outwardly and downwardly under the action of gravity into engagement with the cam roller 44^a on the release arm 43 of the 120

lock, which action rotates the rock shaft 27 and causes the lock arm 29 of lever 28 fixed thereon to swing clear of the path of the catch supporting arm 20 and permit the 5 same to swing to unlocked position. When the car is started, the chain 47 is tightened, thereby causing the cam to swing clear of the cam roller. As shown in the drawing, stops 47^a are provided for limiting the down- 10 ward movement of the cam.

The upper end of the catch supporting arm 20 is provided with a pin 48 which projects rearwardly through an elongated slot 49 provided therefor in the rear side wall of 15 the lock casing 17. In the locked position of the lock catch supporting arm 20, the pin 48 on the upper end thereof projects beyond the rear side wall of the casing, while in the unlocked position of said arm, said pin 20 is positioned with its free end substantially flush with the outer surface of said side walls of said casing. Located alongside the rear side wall of the lock casing is an upright bar 50 whose upper end portion has a slot- 25 and-pin connection 51 with the lock casing, and whose lower end portion has a slot-and-pin connection 52 with a bracket 53 fixed to the angle bar door guides 6. The upper end of the vertical or upright slide bar 50 is 30 provided with a hook 54, which extends into the elevator shaft 1 into the path of the adjacent door arm 10 of the lower door section 4, whereby said bar is adapted to be suspended from said door arm in the closed position of said door section. As shown in the drawings, the slots of the upper and lower slot-and-pin connections 51 and 52 between the bar 50 and the lock casing and door guides, respectively, are each inclined 35 40 upwardly and inwardly towards the elevator shaft whereby said bar is carried upwardly and inwardly towards the elevator shaft when the lower door section is closed and moves downward and outward with respect to said shaft when said lower section is 45 opened. With this arrangement the unslotted portion of the bar 50 is located opposite the end of the pin 48 on the catch supporting arm 20 in the open position of 50 the door and thus prevents movement of said arm to locking position, while the slot of the slot-and-pin connection 51 between said bar and the lock casing is shaped and arranged to register with said pin in the 55 closed position of the door, thereby permitting said arm to move to locking position when the door is closed. The lock casing is provided with an outstanding lug 55 adapted to be engaged by the bar 50 to limit down- 60 wardly sliding movement thereof. It is noted that the upright bar is made long enough to extend below the door arm of the lower section in the fully opened position thereof, in which position the door arm is 65 substantially in contact with the shaft side

of said bar and thus prevents said bar from being shifted in the direction of the shaft to bring the slot of the slot-and-pin connection 51 into register with the pin 48 on the catch supporting arm 20.

The operation of the device is as follows:

When the car stops at the landing, the retiring cam 45 is automatically released and swings outwardly into engagement with the cam roller 44^a on the outer end of the release 70 arm 43 and causes the upper arm 30 of the rock lever 28 on the rock shaft 27 to swing away from the contact posts 36 mounted on the lock casing, which action breaks the contact between the said posts and the contact 80 plate 33 carried by said arm and thus opens the electric circuit which controls the operation of the elevator. Continued swinging movement of the switch carrying rock lever 28 causes the depending lock arm 29 thereof to swing clear of the upper end of the catch supporting arm 20, which arm is prevented from outward swinging position by the pressure exerted thereagainst by the spring-pressed latch bar 12. The operating 85 lever 11 is then operated to cause the latch bar to slide inwardly against the pressure of the spring 14, which action, due to the interlocking engagement of the hooked ends of the latch bar and the catch 24 on the supporting arm 20 therefor, causes said catch to travel outwardly through the opening 18 in the lock casing. During the outward travel of the catch 24, the upwardly inclined inner arm thereof abuts against the bevelled surface 26 of the opening 18 in the lock casing and is forced downwardly, thereby causing the hook 25 on the outer arm of said catch to swing upwardly out of engagement with the notch 16 at the outer end 95 of the latch bar. In the released or unlocked position of the catch supporting arm, the upper end thereof is positioned across the free end of the lock arm 29 of the rock lever 28 and thus prevents said lever from 100 being swung in a direction which will close the electric circuit which controls the operation of the elevator.

The counterweighted door sections 3 and 4 are then separated by a downward pressure on the lower door section 4, which action causes the door arm 10 of the lower section, together with the upright bar 50 supported thereon, to move downwardly. During this downward movement of the upright movable bar 50, the inclined portions of the slots of the slot-and-pin connections 51 and 52 operate to cause said bar to shift laterally into a position in which the body portion of the bar is disposed opposite the pin 48 on the catch supporting arm 20 and thus prevents said arm from being forced inwardly. In this position of the bar 50 the door arm is disposed in abutting relation to the shaft edge of said bar and thus serves to 115 120 125 130

prevent said bar from being shifted to bring the slot therein in register with the pin 48 on the catch supporting arm 20.

When the door is closed the vertically movable bar 50 is carried upwardly with the lower door section and is moved inwardly by the action of the slot-and-pin connections into a position which will bring the upper slot into a position opposite the end of the pin 48 on the catch supporting arm 20. In this position the latch bar 12 is automatically slid into abutting relation with the catch supporting arm 20, thereby forcing said arm to swing inwardly and carry the catch 24 thereon rearwardly into the opening 18 in the lock casing. During the rearward travel of the catch 24, the hooked outer end of the catch swings downwardly into engagement with the notch in the latch bar and the pin 48 on the upper end of the catch supporting arm extends through the upper slot in the vertically movable bar. When the catch supporting arm 20 has moved to locking position, the upper end thereof will have moved clear of the lock arm 29 of the contact carrying lever 28. The starting mechanism of the elevator is then actuated thus disengaging the cam 45 from the roller 44 on the release arm, whereupon the lever 28 swings into a position with its lower arm in front of the catch supporting arm 20 and with its upper switch supporting arm in position to bring the plate 33 therein into contact with the posts 66. With the posts thus positioned the electric circuit of the elevator is closed and the car then leaves the landing.

The hereinbefore described arrangement admits of considerable modification without departing from the invention; therefor I do not wish to be limited to the precise arrangement shown and described.

What I claim is:

1. In an electric elevator, a shaft, a car working therein, doors for closing the door openings in said shaft, a slidable latch bar for each door, an arm mounted for swinging movement towards and away from the end of said latch bar, a catch mounted on said arm and adapted to move into engagement with said latch bar when the arm is swung rearwardly under pressure of said bar, a lever mounted for swinging movement on an axis disposed at right angles to the axis of the catch supporting arm, and a switch for making and breaking an electric circuit controlling the operation of the elevator car, one element of said switch being stationary and the other element thereof being mounted on one arm of said lever for movement therewith into and out of engagement with said stationary element, the free end of said catch supporting arm and the other arm of said lever being disposed in over-lapped relation in the opened and closed positions of said switch, whereby said catch supporting arm prevents movement of said lever to a position which will close said switch until after the catch supporting arm has moved to locking position, and said other arm of said lever prevents unlocking

switch, whereby said other arm of said lever prevents unlocking movement of said catch supporting arm in the closed position of said switch and said catch supporting arm prevents movement of said lever in a direction which will close said switch in the unlocked position of said catch supporting arm.

2. In an electric elevator, a shaft, a car working therein, doors for closing the door openings in said shaft, a slidable latch bar for each door, an arm mounted on the elevator shaft for swinging movement towards and away from the end of said latch bar, a catch mounted on said arm and adapted to move into engagement with said latch bar when the arm is swung rearwardly under pressure of said bar, a switch adapted to make and break an electric circuit controlling the operation of the elevator car, and a movably mounted member in position to cooperate with the free end of said catch supporting arm, one element of said switch being stationary and the other element thereof being mounted on said movably mounted member for movement therewith into and out of engagement with said stationary switch element, said catch supporting arm and said switch supporting member having portions that cooperate with each other in the opened and closed positions of said switch, whereby said switch carrying member prevents unlocking movement of said catch supporting arm in the closed position of said switch and said catch supporting arm prevents opening movement of said switch carrying member in the unlocked position of said catch supporting arm.

3. In an electric elevator, a shaft, a car working therein, doors for closing the door openings in said shaft, a spring projected latch bar for each door, an arm mounted on said shaft for swinging movement towards and away from the end of said latch bar, a catch mounted on said arm and adapted to interlock with said latch bar when the arm moves rearwardly under pressure of said latch bar, a lever mounted on said shaft for swinging movement on an axis disposed at right angles to the axis of the catch supporting arm, and a switch adapted to make and break an electric circuit controlling the operation of the elevator car, one element of said switch being stationary and the other element being mounted on one arm of said lever for movement therewith into and out of engagement with said stationary element, the free end of said catch supporting arm and the other arm of said lever being disposed in overlapped relation in the opened and closed positions of said switch, whereby said catch carrying arm prevents movement of said lever to a position which will close said switch until after the catch carrying arm has moved to locking position, and said other arm of said lever prevents unlocking

movement of said catch supporting arm until after said lever has moved into position to close said switch.

4. In an electric elevator, a shaft, a car working therein, doors for closing the door openings in said shaft, a latch bar for each door, an arm mounted for swinging movement towards and away from the end of said latch bar; a catch mounted on said arm and adapted to move into engagement with said latch bar when the same is moved to latched position, a switch for making and breaking an electric circuit for controlling the operation of the elevator car, and a lever mounted for swinging movement on an axis disposed at right angles to the axis of the catch supporting arm, one element of said switch being stationary and the other element being mounted on said lever for movement therewith into and out of engagement with said stationary element, the free end of said catch supporting arm being adapted in the unlocked position thereof to move into the path of said lever to prevent movement thereof in a direction which will close said switch.

5. In an electric elevator, a shaft, doors for closing the door openings in said shaft, a latch bar for each door, a lock casing secured to the shaft adjacent to said latch bar, a member mounted in said casing for movement towards and away from said latch bar, a catch mounted on said member and adapted to move into interlocking engagement with said latch bar when the latter is pressed against said member and moves it rearwardly, said catch supporting member having a pin projecting therefrom through a slot provided therefor in the adjacent wall of said lock casing, and a member mounted for sliding movement adjacent to said wall of said casing, said door cooperating with said slidable member to move the latter clear of the pin on the catch supporting member in the closed position of said door and to permit said member to move across the end of said pin in the open position of said door to prevent rearward movement of said catch supporting member when the door is opened and the catch supporting member is moved forward to unlocked position.

6. In an electric elevator, a shaft, doors for closing the door openings in said shaft, a spring projected latch bar for each door, a lock casing secured to the shaft opposite the end of said latch bar, an arm pivotally mounted in said casing for swinging movement towards and away from the end of said latch bar, a catch pivotally mounted on said arm and adapted to move into interlocking engagement with said latch bar when the latter is pressed against said arm and swings it rearwardly, said arm having a pin projecting rearwardly therefrom through a slot provided therefor in the adjacent wall of said

said lock casing, and a bar mounted for sliding movement opposite said wall of said casing, said door cooperating with said slideable bar to move the latter clear of the pin on the catch supporting arm in the closed position of said door and to permit said bar to move across the end of the pin on said catch supporting arm in the open position of said door to prevent rearward swinging movement of said catch supporting arm when the door is opened and the catch supporting arm is swung forward to unlocked position.

7. In an electric elevator, a shaft, vertically sliding doors for closing the door openings in said shaft, a horizontally slideable spring projected latch bar for each door, a lock casing secured to the shaft opposite the outer end of said latch bar, an arm pivotally mounted in said casing for vertically swinging movement towards and away from said end of said latch bar, a catch pivotally mounted on said arm and adapted to move into interlocking engagement with said latch bar when the latter is pressed against said arm and swings it rearwardly, said arm having a pin projecting rearwardly therefrom through a slot provided therefor in the adjacent wall of said lock casing, and an upright bar having a slot-and-pin connection with said wall of said casing, said door having a horizontally projecting arm cooperating with said bar to move the same into position with the slot thereof located opposite the pin on the catch supporting arm when the door is closed and to permit said bar to move into a position with its unslotted portion disposed opposite the end of the pin on said catch supporting arm when the door is opened.

8. In an electric elevator, a shaft, vertically sliding doors for closing the door openings in said shaft, a horizontally slideable spring projected latch bar for each door, a lock casing secured to the shaft opposite the outer end of said latch bar, an arm pivotally mounted in said casing for vertically swinging movement towards and away from the end of said latch bar, a catch pivotally mounted on said arm and adapted to move into interlocking engagement with said end of said latch bar when the latter is pressed against said arm and swings it rearwardly, said arm having a pin projecting rearwardly therefrom through a slot provided therefor in the adjacent wall of said lock casing, and an upright bar having slot-and-pin connections with said wall of said casing and said elevator shaft adapted to permit said bar to move into a position with the slot of the slot-and-pin connection between the bar and lock casing in register with the end of the pin on said lock casing and into a position with the body portion of the unslotted portion of said bar opposite said end of said

pin, said door being provided with a door arm adapted during the closing movement of said door to lift said bar and bring the unslotted portion thereof opposite the end 5 of said pin.

9. In an electric elevator, a shaft, vertically sliding doors for closing the door openings in said shaft, a horizontally slideable spring projected latch bar for each door, a 10 lock casing secured to the shaft opposite the outer end of said latch bar, an arm pivotally mounted in said casing for vertically swinging movement towards and away from the end of said latch bar, a catch pivotally 15 mounted on said arm and adapted to move into interlocking engagement with said end of said latch bar when the latter is pressed against said arm and swings it rearwardly, said arm having a pin projecting rearwardly 20 therefrom through a slot provided therefor in the adjacent wall of said lock casing, and an upright bar having slot-and-pin connec-

tions with said wall of said casing and said elevator shaft adapted to permit said bar to move into a position with the slot of the 25 slot-and-pin connection between the bar and lock casing in register with the end of the pin on said lock casing and into a position with the body portion of the unslotted portion of said bar opposite said end of said pin, said door being provided with a door arm adapted during the closing movement of said door to lift said bar and bring the unslotted portion thereof opposite the end 30 of said pin, said door arm cooperating with said bar in the opened position of the door to prevent said bar from being moved into a position with its slotted portion in register with the end of the pin on said catch supporting arm.

Signed at St. Louis, Missouri, this 16th day of May, 1928.

JULIUS A. SCHWEIG.
